UNITED STATES PATENT OFFICE.

GISEBERT L. BOSSARD, OF LOUDONVILLE, NEW YORK.

FLASHER.

Application filed June 17, 1925. Serial No. 37,693.

This invention relates to devices of the type employed for the intermittent flashing or lighting of electric lights, and the like.

An object of the invention is to provide an improved electric flasher which will flash any of a plurality of groups of lights at desired intervals; which will be maintained in operation electrically; with which the desired time interval between flashings may be varied and accurately controlled; with which the changes in circuit conditions will be effected rapidly so as to avoid arcing at the points where the circuits are made and broken; and which will be simple in construction, durable, efficient, compact and relatively inexpensive.

A further object is to provide an improved flasher in which the operating mechanism will be enclosed in a casing to prevent tampering by unauthorized persons and having provision for the regulation of the time interval and the making of the necessary circuit connections to the mechanism without interfering with the tampering preventing feature.

Various other objects and advantages will appear from the following description of one embodiment of the invention, and the novel features will be particularly pointed out hereinafter in connection with the appended claims.

In the accompanying drawing:—

Fig. 1 is a front elevation of a flasher constructed in accordance with the invention and with the protecting door opened;

Fig. 2 is a sectional elevation taken from front to rear;

Fig. 3 is a sectional front elevation of a portion of the mechanism of the same;

Fig. 4 is a sectional plan through a portion of the mechanism to illustrate other details;

Fig. 5 is an enlarged front elevation of the casing illustrating the protecting wall within the door, and illustrating the manner of preventing tampering;

Fig. 6 is a section through one of the seals taken on the line 6—6 of Fig. 5;

Fig. 6^a is a similar section taken through the supporting means for the mechanism, at a point where a seal is not employed, taken on the line 6^a—6^a of Fig. 5;

Fig. 7 is an elevation of the oscillating support for one of the circuit make and break elements;

55

Fig. 8 is a wiring diagram of the electrical connections of the flasher.

60

Fig. 9 is an enlarged rear elevation of parts of the mechanism, the upper positions of the parts, shown in dotted lines, corresponding to the positions of the parts of the mechanism as shown in Figs. 1 and 2; and

Fig. 10 is a plan view of the parts of the mechanism appearing in Fig. 9.

65

In the illustrated embodiment of the invention, the operating mechanism is enclosed within the casing 1, having a door 2 and a protecting wall 3 closing the open face of the casing within the door. The active mechanism for controlling the electric circuits is carried by a frame 4, which is secured by screws or bolts 5 to lugs 6 projecting from the interior of the casing, the bolts 5 passing through long sleeves 4^a provided upon the frame 4 and at their rear ends screwing into the rear plate of the frame as shown in Fig. 6^a. The sleeves 4^a pass through spacing sleeves 4^b interposed between the protecting wall 3 and the rear plate of the frame 4, as most clearly shown 70 in Figs. 6 and 6^a. The screws or bolts 5 permit removal of the frame 4 with the mechanism carried thereby when cap nuts 5^a at the outer ends of the bolts are removed 75 to allow the sleeves 4^a to slide outwardly. The protecting wall 3 is carried by the sleeves 4^a at their outer ends, packing being placed between its margin and an internal flange 7 at the open face of the casing. Nuts 8 threaded upon the outer ends of the 80 inner sleeves 4^a confine the protecting wall 3 thereon and against the spacing sleeves 4^b upon the inner sleeves 4^a.

85

An electromagnet 9, having windings 10 and spaced polar ends or extensions 11, is 90 mounted in the frame 4 at the rear thereof, and an armature 12 is fixed upon a shaft 13 that is rotatably mounted in the space between the polar ends 11, so that when the electromagnet is energized, the armature 12 95 will be rotated into the positions shown in Fig. 1. The shaft 13 at one end carries a laterally extending arm 14 which is connected to a weight 15 which at its free end

100

tends to depress the arm, the arm 14 being adjustably secured to the armature shaft 13 by any suitable means, such as by a set screw 16 carried by the arm 14 and engaging with 5 the end of the shaft which passes through the arm 14. When the armature 12 is rotated into the position shown in Fig. 1, the arm 14 will also be rotated to lift the weight 15 into approximately the position there shown, 10 and also shown in such upper position by dotted lines in Fig. 9. The intermediary connections between the arm 14 and the weight 15, which are shown most clearly in Figs. 9 and 10 will be hereinafter described. 15 A crank arm 17 is secured to the other or forward end of the armature shaft 13, and at its free end the crank arm 17 is provided with a crank pin 18, projecting forwardly therefrom and parallel to the shaft 20 13. A bearing pin 19 extends between and through two transversely disposed parallel frame strips 20 and 21, at a point slightly above the armature shaft 13 and parallel thereto, and upon this bearing pin 19, two 25 elements 22 and 23 are mounted for oscillatory movement relatively to one another about the axis of the pin 19.

The element 23 is in the nature of an arm extending downwardly past the forward 30 end of the armature shaft 13 and having at its lower end a slot 24 elongated lengthwise thereof through which the pin 18 on the crank arm 17 passes, so that the arm 23 and crank arm 17 will always oscillate con- 35 comitantly. Inasmuch as they oscillate about different axes, however, the elongated slot 24 is necessary in order to permit of the limited movement of the pin 18 toward and from the axis of the pin 19 during the oscillation of the two arms together. The upper end of the arm 23, which is above the bearing pin 19, is pointed or tapered, as at 40 25, for a purpose which will appear presently.

45 The element 22 is tubular at its upper end, and slotted at its lower end so as to provide two arms 26 and 27, the forward arm 27 being longer than the arm 26, and the two arms straddling the upper end of 50 the arm or element 23. The tapered end 25 of the arm 23 passes through the element 22 in close proximity to the upper end of the slot forming the two arms 26 and 27. The two arms 26 and 27 are pivotally mounted on the pin 19 for movement about the axis of the pin during the flashing operations as will appear presently.

The element 22, as explained, is tubular having a longitudinally extending inner 60 passage 28 from the beginning of the forked portion to its upper end. In this tubular passage, a helical compression spring 29 is disposed and confined by a movable plug 30 and lock nut 30a, which plug is threaded 65 into the upper end of the element so as to

compress the spring 29 to an extent. A spherical ball 31 is disposed in the lower end of the bore, being held from complete projection therefrom by a slight convergence in the bore at the lower end, the ball, however, projecting through the open lower end of the bore and within the path of the tapered end 25 of the arm 23. 70

When the arm 23 is oscillated, the tapered end 25 thereof will pass through the element 22 and cam the ball 31 upwardly, thereby compressing the spring 29 in the bore of the element, and as soon as the point of the tapered end 25 has passed the center of the ball 31, the spring 29 will act through the ball to press against the inclined rear face or surface of the tapered end and exert a camming action thereon in the direction in which it is moving at the particular time. This action occurs whether the direction of movement of the tapered end 25 to the forked end of the element 22 is in one direction or the other. The ball 31 is free to rotate universally in the lower end of the bore 28 and, therefore, acts somewhat as a 80 ball-bearing in riding up and down the tapered surface of the arm 23.

A U-shaped strap 32 is disposed over the forward end of the pin 19 and secured by screws 33 to the long arm 27 of the element 22, so as to oscillate therewith about the axis of the pin 19, and this strap 32 carries a tube support 34, preferably largely or entirely of insulating material. The support 34 includes a pair of blocks 35 95 somewhat T-shaped, as shown in Fig. 7, separated by interposed insulated barriers, and each having upon the upper face of the head of the T a plurality of spring clips 36 for mounting two contact tubes 37 100 and 38 which extend in the plane of the block, that is from side to side of the casing. The two tubes 37 and 38 are approximately parallel to one another, spaced apart from front to rear of the casing, and located immediately behind the protecting wall 3 at the open face of the casing. The protecting wall 3 may have a transparent window 39 at approximately the position of the tubes so that their position may be 105 observed without removing the protecting wall.

The tubes form part of a suitable liquid make and break mechanism, or circuit controller, somewhat of the type disclosed in 110 the co-pending application of Gisbert L. Bossard, et al, Serial No. 385,609, filed June 1st, 1920. Any suitable construction of the tube may be employed but for purposes of simplicity the tube may be made of glass, 115 and is provided with a plurality of depending pockets 40 at each end, the pockets at each end being spaced apart lengthwise of the tube. Each tube is partially filled with a quantity of liquid 41, such as mer- 120

cury, which is capable of conducting an electric current. In each pocket 40, an electrode or contact terminal 42 is disposed for contact with the liquid when the liquid 5 enters the pocket. In order to stifle any tendency to arcing, the air is exhausted from the tube and several inert gases are sealed into the tube.

Thus, when the tube tilts into one inclined 10 position, such as shown in Fig. 1, the liquid will run into the lower end, fill the pockets at that end and bridge them, with the result that the two electrodes at that end are electrically connected through the liquid body.

15 When the tube tilts in the opposite direction upon the oscillation of the blocks 35 with the element 22, the liquid body of each tube will run into the opposite end, fill the pockets at that end, and electrically connect 20 the contacts or electrodes in these pockets to that end. In doing so it will break the connection between the pockets at the other end, and therefore interrupt the electrical circuit between the electrodes in those pockets. 25 The tilting of the tubes is due to the unique quick make-and-break mechanism, hereinafter more particularly described, sufficiently rapid to not only prevent arcing, but by preventing the reduction in cross sectional area of the mercury column, eliminates 30 undue heating of the glass tube and the resultant breakage thereof.

Each block 35 is provided with a contact strip 43, which extends from end to end of 35 the head of the block, and at the ends, where it is exposed, carries screw binding posts 44, and intermediate of its ends has an exposed lateral extension 45 carrying a binding screw 46. Each block is also provided, upon the 40 sides of the leg of the T, with binding screws 47 for a purpose which will appear presently. It is to be understood, of course, that the binding screws 44, 46 and 47 shown in the drawings are merely illustrative and that 45 in lieu thereof any suitable means may be employed to provide connections for the several wires of the circuits. A circuit wire 48 is connected to each binding screw 46 so as to establish electrical connection to the binding screws 44, and from the latter, 50 wires 49 are connected, one to each end of the tube carried thereon, so that no matter which way the tube is inclined, the liquid body will be electrically connected to the current supply wire 48. Any number of 55 connected blocks and tubes may be utilized in order to control the desired number of circuits as will be explained later. Wires 50 connect the electrodes of the remaining 60 pockets in the ends of the tubes to the binding screws 47, and from these binding screws circuit wires lead to the circuit connections as will be explained shortly.

In order to control the rotation of the 65 armature shaft 13, both under the pull of

the armature and of the weight 15, the shaft is provided with a rigidly connected arm 51 (see Fig. 3) which is connected at its free end to a sleeve 52 that is slidably mounted upon a rod 53. The rod 53 is provided with 70 a collar 54 intermediate of its ends, and with a nut 55 at its lower end, leaving a space between them in which the sleeve 52 is disposed so as to slide lengthwise of the rod to the extent limited by the collar 54 and 75 the nut 55. Between the sleeve 52 and the collar 54 a helical compression spring 56 is disposed upon the rod, so that when the sleeve 52 is shifted toward the opposite end of the rod 53, it will compress the spring 80 85 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 A link 67 is pivoted at 68 to the nut 66, and is also pivotally connected by a pin 69 to a crank arm 70, which is fitted over the outer end of the needle 61, being held in 125 different angular positions thereon by suitable means, such as by a set screw 71. Thus, by rotating the button 65, the nut 66 may be reciprocated in a direction between the front and rear, and in doing so will oscil-

late the crank arm 70 and thereby rotate the needle 61 in a direction to either open or close the vent 60 in the casing. By variation in the effective opening of the vent 60, the air resistance to travel of the armature shaft may be varied.

The shell of the dash pot may be mounted upon the frame in any suitable manner, but preferably the open end of the shell is placed upon a section 72 of the frame 4, being confined in a slight recess in the face of the section 72 by a flange or ring 73 which is secured to the section 72 in any suitable manner, not shown. By mounting the dash pot 15 in this manner it becomes self-cleaning, preventing dust, etc., from lodging in it.

The electrical circuit connections in Figs. 1 to 6 have been largely omitted in order not to conceal the details of construction, but 20 these connections are shown in diagram in Fig. 8. Referring then to Fig. 8, the various circuits will be explained. The current is supplied through line wires 74 and after 25 passing through line fuses 75 and a main controlling switch 76, these line wires are designated as wires 77 and 78 and are preferably connected to second fuses 79. From 30 the fuse 79 to which the wire 77 is connected two branch conductors 80 lead to the circuit leads 48 from the central parts of the two blocks 35 that mount the tubes. By reason 35 of these connections, current will always be supplied to an electrode in each end of each tube.

A conductor 81 is connected to a binding screw 47 which is electrically connected by a wire 50 to the electrode in one end of one of the tubes, such as 37, and leads to the 40 electromagnet windings 10. The other end of the electromagnet winding is connected by a wire 82 to the other line wire 78 and fuse 79, thus providing for completing one 45 circuit between the two line wires and through the tube in a manner presently to be described.

The two tubes illustrated are adapted to 50 control four loads, designated *a*, *b*, *c* and *d* in the diagram, each load consisting of one or more electric lights, which it is desired to light intermittently and alternately. The loads *a* and *b* have a common return wire 83, and the loads *c* and *d* have a common return wire 84. These two return wires 83 and 84 are connected to the line wire 78. Another conductor 85 is connected at one end to the conductor 81 extending between the tube 37 and the electromagnet, and at its other end is connected to the other side of one of the loads, such as *d*, so that whenever the electromagnet is energized, the lights of the load 60 *d* will be illuminated, thus completing another circuit to the two line wires 77 and 78 through the tube 37, it being noted that the

electrodes in the left end of the tube 37 are, 65 through the above described connections, in the circuit of the load *d* as well as in the circuit of the electromagnet 10, and it being further noted that the electromagnet 10 and the load *d* are connected to the line wires 70 77 and 78 in parallel relation with each other.

A conductor 86 is connected through a binding post 47 and a wire 50 to an electrode 75 in the opposite end of the tube 37, and is also connected to one side of the load *a*, so that when the current is completed through that end of the tube 37, the lights of the load *a* will be illuminated.

A conductor 87 at one end is connected through a binding screw 47 and a wire 50 to an electrode in one end of the tube 38, and at its other end is connected to one side of the load *b*, so that when this tube is tilted to one side, the lights of the load *b* will be illuminated through the completion by the liquid of the circuit to conductor 87.

Still another conductor 88 is connected at one end through a binding screw 47 and a wire 50 to an electrode in the other end of the tube 38, and at its other end is connected to one side of the load *c* in order to complete the circuit to the lights of the load *c* whenever the tube 38 is tilted to one particular side.

Assuming that the tubes are tilted to the left as shown in Fig. 8, the liquids 41 in the tubes will run to the left hand ends of both tubes and complete electrical circuits between all electrodes in the lower ends of each tube. One circuit will be completed through wires 77, 80, 48, tube 37, wire 81, electromagnet windings 10 and wire 82 back to the other side of the line, and also a branch line through the wire 85 to the load *d*. Thus, through the tube 37 a circuit is completed to the electromagnet windings 10 and the load *d*, and the lights of the latter will be illuminated.

Simultaneously the liquid 41 of the tube 38 will complete a circuit between the wires 77 and 80 to the wire 88, which leads to the load *c*, and therefore the lights of the load *c* will also be illuminated at this time. The power for the two loads *c* and *d* will, therefore, be divided between the two tubes and sufficient current will be also passed through one of the tubes, for instance, 37, to energize the windings 10 of the electromagnet. The electromagnet being energized, will exert a rotary torque upon its armature, tending to move it into the position shown in Fig. 1, that is, so as to extend directly between the polar ends 11.

As the armature moves into this position, it will elevate the weight 15, and its travel will be resisted by the air in the dash pot

to an extent depending upon the effective opening of the vent 60 of such dash pot. The electromagnet windings 10 will, therefore, remain energized for a short interval, 5 and as the armature approaches the position shown in Fig. 1, the crank arm 17 of the armature shaft will have rocked the arm 23 until the pointed end has moved slightly past the center of the ball 31, where- 10 upon the pressure of the spring 29 upon the ball will cause the ball to ride downwardly upon the rear inclined face of the tapered end 25, and this camming action between the two elements 22 and 23 will 15 cause a movement of the element 22 to its other limit of movement, and in this limited movement of the element 22, the tubes will be tilted into a position oppositely inclined from that which they previously occupied. 20 This tilting movement is relatively rapid and, therefore, the liquid 41 will roll into the opposite end of the tube with sufficient rapidity to break the circuits previously established without material arcing between 25 the electrodes previously connected. The limits of throw of the element 22 will be determined by adjustable abutments 89, shown in the drawings as in the form of screws but which may be of any suitable 30 form, with which the lower end of the arm 27 engages as it oscillates from side to side. These screws are threaded through a portion of the frame and may be adjusted to increase or decrease the extent of throw of 35 the element 22 and thereby the angles of inclination of the tubes at the limits of their movements.

When the tubes have moved into their other inclined positions opposite from those 40 shown in Fig. 8, and into the positions shown in Fig. 1, the liquids 41 will have run into the other or right hand ends of the tubes and have completed the circuits to the load wires 86 and 87 thereby again 45 to illuminate the lights of the loads *c* and *d*, at the same time opening the circuits through the wires 81 and 88. The opening of the circuit through the wire 81 opens the circuit through the load wire 85, and 50 the circuit through the load wire 88 also having been opened, the lights of both of the loads *c* and *d* will be extinguished. Upon the opening of the circuit to wire 81, the electromagnet windings 10 will be deener- 55 gized and the armature released. The weight 15 will then exert a rotary torque upon the armature shaft 13 in a direction to rotate it in the opposite direction, that is, in a direction to carry the armature away 60 from the position shown in Fig. 1, in a clockwise direction, and this rotation of the armature shaft caused by the weight 15 will be resisted by the pressure of the atmosphere on the piston 58 because of the partial 65 vacuum now formed in the dash pot, the

degree of resistance being dependent upon the effective opening of the vent 60.

During the descent of the weight 15, the crank arm 17 on the armature shaft 13 will slowly rock the lower end of the arm 23 in 70 the opposite direction, that is clockwise in Figs. 1 and 3. The tapered end 25 will slowly cam the ball 31 upwardly, and as soon as the ball 31 rides over the tip end of the arm 23, it will ride down the other 75 inclined face thereof, and in doing so will cam the element 22 in the opposite direction, that is, to the left, in Figs. 1 and 3 so as to tilt the tubes back into the original positions shown in Fig. 8. 80

This tilting movement is relatively rapid once it is started by the ball riding over the pointed end 25 of the arm 23, and tips the tubes with sufficient rapidity to prevent arcing where the circuits are broken. The 85 liquids in passing into the new lower ends again, will re-establish the first described connections to the electromagnet windings 10 and the loads *c* and *d*, at the same time extinguishing the circuits or lights of the 90 loads *a* and *b*. The energization of the electromagnet windings 10 will cause another operation of the armature 12 into the position shown in Fig. 1, which movement will, of course, be again resisted by the air 95 in the dash pot and the weight 15, and when the movement has continued sufficiently far, the ball 31 will ride over the point of the arm 23 and effect a tilting of the tubes back into the position shown in Fig. 1. 100

This operation will continue with an alternate tipping of the tubes at specific intervals, and during these tilting movements of the tubes, the lights of the loads *a* and *b*, *c* and *d* will be flashed alternately, that is, 105 the lights of loads *a* and *b* will be illuminated alternately with those of loads *c* and *d*. By rotating the buttons 65, the effective opening of the vent 60 may be varied, so as to vary the effective air resistance of the 110 dash pot and thereby the interval elapsing between the tilting movements of the tubes.

Inasmuch as a number of circuit connections must be effected between the loads and the interior of the casing, it is desired to 115 prevent access by unauthorized persons to the interior casing; the connections from the tubes and electromagnet windings are made to binding posts 90 carried by a support 91 of the frame, and from these binding posts additional connections may be made to further binding posts 92, secured to a support 93 upon the bottom wall of the casing, so that when the frame with the operating mechanism is to be removed, it is 120 merely necessary to disconnect the wires between the binding posts 90 and 92.

The casing is provided with an extension 94 on its lower end, which is not directly in communication with the interior of the body 130

of the casing 1 except by an opening 95 which is closed by a horizontal flange of the support 93. Suitable contact strips 96 connect the binding post 92 within the main chamber of the casing 1 with the binding posts 97 in the chamber of the auxiliary or lateral extension casing 94. The auxiliary casing 94 has conduit openings 98 through which the various circuit connections from the line wires 77 and 78 and the load wires may be connected. The proper connections and calibrations are made before the main casing is closed, and these connections extend to the binding posts 97 in the lateral extension or auxiliary casing 94. It is merely necessary for the user to remove the cover 99 of the auxiliary casing 94 and make the necessary circuit connections between the binding posts and the line and load wires without any occasion for opening the main door 2, or removing the protecting wall 3.

In order to indicate when the protecting wall 3 has been removed and unauthorized access had to the interior of the mechanism, a cup nut 100 is provided upon the outer end of one or more of the sleeves 4^a, and within the cup one of the securing nuts 5^a is located and threaded upon the screw or bolt 5. The opening of the cup may then be filled with sealing wax or metal to conceal the nut 5^a. Thus, in order to remove the protecting wall 3, it would be necessary to disturb the sealing wax or metal in the cup 100 before the protecting wall may be removed to provide access to the interior of the mechanism and, if the sealing wax or metal has a private seal impression thereon, one can readily tell whether or not the protecting wall 3 has been removed. This is a certain indication of whether or not tampering by unauthorized persons may have occurred. It is to be noted that the same protection is afforded against unauthorized removal of the frame 4 and the mechanism carried thereby as a whole.

In order to limit the movement of the armature to the desired range of operative positions, especially while the flasher is rendered entirely inoperative by the opening of the switch 76, adjustable abutments shown in the drawings as in the form of screws, but which may be of any suitable form, may be provided in the frame within the path of the lower end of the arm 23 at opposite sides thereof, and these screws may be adjusted so as to vary the limits of travel as desired.

It has been found that the spring 56 is particularly useful in promoting the efficiency of the mechanism because during the initial movement of the armature, the spring 56 is compressed and exerts a yielding pressure upon the dash pot. The function of the spring 56 is to compensate for voltage fluctuations and the resultant change in the pull

of the electromagnet 9. By reason of the employment of this spring 56 the advantageous manner of operation is as follows: The armature 12 when subjected to the pull of the magnet will completely compress the spring 56. When thus completely compressed the spring 56 expends its stored energy by propelling the piston 58 upwards. This manner of operation results in a precision of movement that is independent of fluctuations in voltage in the current supply.

The hereinbefore mentioned connections between the arm 14 and the weight 15 will now be described, reference being had more particularly to Figs. 1, 2, 9 and 10, taken in connection with Figs. 3 and 4. The weight 15 is rigidly fixed upon the outer or free end of a rod 102 the other end of which is rigidly fixed to the outer end of a hub member 103 which at its other end is pivoted upon a pin 104 in alignment with the rod 102 and carried at its inner end by the back plate of the frame 4 and at its outer or rear end by a U-shaped bracket 105 which is attached to the rear side of the back plate, the hub 102 being shown as spaced from the frame plate by a filler sleeve 106 (Fig. 2) on the pivot pin 104. The rod 102 together with its pivoted hub 103 forms a weight-carrying lever arm extending transversely of the casing 1 in the back part thereof. The weight 15 is supplemented by an auxiliary weight 107 which is an adjustment weight slideable along the rod 102 and which may be clamped in adjusted position on the rod by means of a set screw 108, whereby the effect of the weights upon the lever-arm may be varied. The upper end of a link 109 is pivoted at 110 to the outer end of the hub member 103 on its lower side out of alignment with the rod 102, and at its lower end the link 109 is pivoted at 111 to the free end of the laterally extending arm 14, which, as hereinbefore described is adjustably secured upon the rear end of the armature shaft 13.

In Figs. 9 and 10, for purposes of illustration, the parts of the mechanism just described are shown in full lines at an intermediate position corresponding to a position of movement, either upward or downward, in the operation of the device, while in Fig. 9 the lower position of the parts shown in dot and dash lines corresponds to the de-energized condition of the magnet 9, and the dotted line upper position of the parts corresponds to the energized condition of the magnet, this upper position of the parts being shown in Figs. 1 and 2.

By an inspection of Fig. 9 it will be noted that the link 109 and the hub element 103 taken together form in effect a pair of toggle links.

In the operation of the mechanism in the de-energized condition of the magnet 9, in

- which the weights 15 and 107 are at their lower positions (see Fig. 9), the link 109 is in an inclined position with its upper pivot 110 more nearly in line with its lower pivot 11 than it comes in any other positions of the parts of the mechanism, the toggle formed by the link 109 and the hub member 103 being nearly straightened out, it being also noted that the link 109 extends substantially at right angles to the arm 14, so that the weights 15 and 107 exert their greatest force and apply a maximum torque in a counterclockwise direction, as viewed in Fig. 9, to the armature shaft 13 and therefore offer their greatest resistance to rotation of the armature shaft in the opposite direction.
- When the magnet 9 is energized the torque thereby applied to the armature 12 in a clockwise direction as viewed in Fig. 9 gradually lifts the weights at the same time causing the tapered end 25 of the arm or snap blade 23 to raise the ball 31 and compress the snap movement spring 29, as hereinbefore described, it being noted that in the initial part of the operation the spring 29 is most extended and therefore offers the least resistance to compression. As the rotation of the armature continues the center line of the link pivots 110 and 111 draws farther away from the hub pivot 104 so that the force required of the armature in raising the weights gradually grows less as the force required of the armature for further compressing the spring 29 grows greater, so that thereby the increase in force required in compressing the spring is compensated for by the decrease in force required in raising the weights, this compensating action continuing until the armature 12 has reached its limit of movement and the spring 29 under its maximum compression has snapped the ball 31 over the point of the tapered cam end 25, as shown in Figs. 1 and 3, it being noted that at this time of greatest compression of the spring 29 the link 109 extends substantially at right angles to a line passing through its upper pivot point 110 and the pivot point 104 of the hub member 103.
- When the magnet 9 is de-energized by the snap movement of the tube-tilting element 22 the weights 15 and 107 begin to rotate the armature 12 in the opposite or counterclockwise direction as viewed in Fig. 9, the weights now applying a minimum force corresponding to the most extended condition and therefore least compression of the spring in which the least amount of force is required to compress it. As the weights descend their effective power to further compress the spring gradually increases as the opposing resistance of the spring increases. When the armature 12 has reached its limit of movement in this counterclockwise direction as viewed in Fig. 9, with the magnet 9 in de-energized condition and the armature being rotated by the weights, the spring 29 will be under its greatest compression and the weights will be applying the greatest force against its increased resistance, by reason of the fact that the effective power of the weights has been gradually multiplied, thereby compensating for the increasing resistance of the spring as it is further compressed. It is to be noted in this connection that a center line from the hub pivot 104 passing through the upper pivot 110 of the link 109 and extended therefrom now passes the closest that it does at any time to the pivot 111 of the link on the armature shaft arm 14, the toggle formed by the hub member 103 and the link 109 now being the most nearly straight, which obviously accounts for the increasing power of the weights to overcome the increasing opposition of the spring as the ball 31 rides up the incline of the tapered cam end 25. When the armature 12 has reached this limit of its movement and the spring 29 has snapped the ball 31 over the point of the tapered cam end 25, the magnet 9 will again be energized by the tilting of the tubes from the position thereof shown in Fig. 1 to the position shown in Fig. 8, and the first part of the complete cycle of operation begins over again.
- It will now be clear that the above described lever and link or toggle connection between the armature shaft and the weights 15 and 107 has a compensating action in both directions of movement of the parts, in the one case multiplying the power of the energized armature to lift the weights and overcome the increasing resistance of the spring 29 and in the other case multiplying the power of the weights to overcome the increasing resistance of the spring, thereby effectively contributing to the assured smooth and continuous operation of the entire mechanism.
- It will be obvious that various changes in the details and materials, which have been herein described and illustrated in order to explain the nature of the invention, may be made by those skilled in the art within the principle and scope of the invention, as expressed in the appended claims.
- I claim:
1. An electric flasher comprising a driver element and a driven element relatively movable and acting upon one another for a snap operation of the driven element in opposite directions when the driver element moves alternately in opposite directions beyond critical intermediate positions, electrically controlled means for operating the driver element in opposite directions, a circuit controller including a pivotally mounted tube containing contacts and a conducting fluid operated by said driven element and

- controlling the activity of said means to cause alternate movements of said driver element, and means for retarding the progress of the movements of the driver element.
5. 2. An electric flasher device, comprising a driver element and a driven element relatively movable and acting upon one another for a snap operation of the driven element in opposite directions when the driver element moves alternately in opposite directions beyond critical intermediate positions, electrically controlled means for operating the driver element alternately in opposite directions, a circuit controller including a pivotally mounted tube containing contacts and a conducting fluid operated by said driven element and controlling the activity of said means to cause alternate movements of said driver element, and means for retarding the progress of the movements of the driver element in both directions. 70
- 10 15 20 25 30 35 40 45 50 55 60 65 70 75 80 85 90 95 100 105 110 115 120 125 130
3. An electric flasher device, comprising a driver element and a driven element relatively movable and acting upon one another for a snap operation of the driven element in opposite directions when the driver element moves alternately in opposite directions beyond critical intermediate positions, means, including a weight, for operating the driver element in one direction, electromagnetic means for operating the driver element in the opposite direction and at the same time elevating said weight for a new operation, a circuit controller including a pivotally mounted tube containing contacts and a conducting fluid carried by said driven element and controlling the activity of said electromagnetic means, so as to cause alternate movements of said driver element, and means for retarding the progress of the movements of the driver element in both directions. 90
4. An electric flasher device, comprising a driver element and a driven element pivoted for independent movement in different parallel planes and acting upon one another for a snap operation of the driven element in both directions when the driver element moves alternately in opposite directions beyond critical intermediate positions, electrically controlled means for operating the driver element in opposite directions, a circuit controller including a pivotally mounted tube containing contacts and a conducting fluid operated by said driven element and controlling the activity of said means to cause alternate movements of said driver element, and means for retarding the progress of the movements of the driver element. 110
5. An electric flasher device, comprising a driver element and a driven element pivoted for independent movement in different parallel planes and acting upon one another for a snap operation of the driven element in opposite directions when the driver element moves alternately in opposite directions beyond critical intermediate positions, electrically controlled means for operating the driver element in opposite directions, a circuit controller including a pivotally mounted tube containing contacts and a conducting fluid operated by said driven element and controlling the activity of said means to cause alternate movements of said driver element, and means for retarding the progress of the movements of the driver element. 120
- parallel planes and acting upon one another for a snap operation of the driven element in opposite directions when the driver element moves alternately in opposite directions beyond critical intermediate positions, electrically controlled means for operating the driver element in opposite directions, a circuit controller including a pivotally mounted tube containing contacts and a conducting fluid operated by said driven element and controlling the activity of said means to cause alternate movements of said driver element, and means for retarding the progress of the movements of the driver element in both directions. 80
6. An electric flasher device, comprising a driver element and a driven element mounted for independent movement in different parallel planes, the driver element having oppositely inclined cam surfaces, said driven element having a spring actuated member riding up and down said cam surfaces of the driver element during relative passing movement between said elements, means for limiting the movement of the driven element whereby during oscillations of the driver element in opposite directions beyond critical intermediate positions, the said member of the driven element will be forced to ride up one of said cam surfaces until the critical point is reached and then in riding down the other inclined cam surface will, through the action of its actuating spring, force the driven element to its other limit of movement, a circuit controller operated by said driven element, and means adapted to continuously operate said driver element alternately in opposite directions beyond critical intermediate positions. 90
7. An electric flasher device, comprising a pivoted driver element, a driven element, said elements being mounted for independent movement in parallel planes, the driver element having oppositely inclined cam surfaces, said driven element having a spring actuated member riding up and down said cam surfaces of the driver element during relative movement between said elements, means for limiting the pivotal movement of the driven element whereby during movements of the driver element in opposite directions beyond critical intermediate positions the contact member of the driven element will be forced to ride up one of said cam surfaces until the critical point is reached and then in riding down the inclined surfaces will, through its actuating spring, force said driven element to its other limit of movement, a circuit controller operated by said driven element, means adapted to continuously operate said driver element alternately in opposite directions beyond critical intermediate positions, and means for retarding the movements of the driver element. 100

8. An electric flasher device, comprising a driver element and a driven element mounted for independent movement in parallel planes, the driver element having oppositely inclined cam surfaces, said driven element having a spring actuated member riding up and down said cam surfaces of the driver element during relative movement between said elements, means for limiting the movement of the driven element whereby during oscillations of the driver element in opposite directions beyond critical intermediate positions the contact member of the driven element will be forced to ride up one of said cam surfaces until the critical point is reached, and then in riding down the inclined surfaces will, by the action of its spring, force said driven element to its other limit of movement, a circuit controller operated by said driven element into different operative conditions, means for operating the driver element in one direction, electromagnetic means controlled by said controller for operating said driver element in the opposite direction and storing energy in the prior actuating means.
9. An electric flasher device, comprising a driver element and a driven element mounted for independent movement in parallel planes, the driver element having oppositely inclined cam surfaces, said driven element having a spring actuated contact member riding up and down said cam surfaces of the driver element during relative movement between said elements, means for limiting the movement of the driven element whereby during oscillations of the driver element in opposite directions beyond critical intermediate positions the contact member of the driven element will be forced to ride up one of said cam surfaces until the critical point is reached, and then in riding down the inclined surfaces will, by the action of its spring, force said driven element to its other limit of movement, a circuit controller operated by said driven element into different operative conditions, means for operating the driver element in one direction, electromagnetic means controlled by said controller for operating said driver element in the opposite direction and storing energy in the prior actuating means, and means for retarding the progress of the movements of the driver element in at least one direction.
10. An electric flasher device, comprising a driver element and a driven element pivoted for independent movement in parallel planes, the driver element having oppositely inclined cam surfaces, said driven element having a spring actuated member riding up and down said cam surfaces of the driver element during relative pivotal movement between said elements, means for limiting the pivotal movement of the driven element whereby during oscillations of the driver element in opposite directions beyond critical intermediate positions, the member of the driven element will be forced to ride up one of said cam surfaces until the critical point is reached, and then in riding down the inclined surfaces will force itself to its other limit of movement, a circuit controller operated by said driven element into different operative conditions, means for operating the driver element in one direction, electromagnetic means controlled by said controller for operating said driver element in the opposite direction and storing energy in the prior actuating means, and means for retarding the progress of the movements of the driver element in both directions.
11. An electric flasher device, comprising a driver element and a driven element independently movable in parallel planes and acting upon one another for a snap operation of the driven element in both opposite directions when the driver element moves alternately in opposite directions beyond critical intermediate positions, an elongated tube mounted for tilting oscillation into oppositely inclined positions concomitantly with the movements of the driven element, an electrically conducting liquid partially filling said tube, spaced electrodes in the ends of the tubes arranged to be electrically bridged by the contained liquid when the tube tilts alternately into oppositely inclined positions, and means for operating the driver element alternately in opposite directions and controlled by the contacts in said tube, and means for retarding the progress of the movements of the driver element.
12. An electric flasher device, comprising a driver element and a driven element independently pivoted for oscillation in parallel planes and acting upon one another for a snap operation of the driven element in both opposite directions when the driver element moves alternately in opposite directions beyond critical intermediate positions, an elongated tube mounted for oscillation into oppositely inclined positions concomitantly with the oscillations of the driven element, an electrically conducting liquid partially filling said tube, spaced electrodes in the ends of the tubes arranged to be electrically bridged by the contained liquid when the tube tilts alternately into oppositely inclined positions, means for operating the driver element alternately in opposite directions and controlled by the contacts of said tube, and means for retarding the progress of the movements of the driver element in both directions.
13. An electric flasher device, comprising a driver element and a driven element mounted for independent movement in parallel planes and acting upon one another for

- a snap operation of the driven element in opposite directions when the driver element moves alternately in opposite directions beyond critical intermediate positions, an elongated tube mounted to be tilted into oppositely inclined positions by the driven member during its movements in opposite directions, means for operating said driver element alternately in opposite directions 10 beyond said critical intermediate positions, a plurality of contacts in each end of the tube, means for supplying current to one contact in each end of the tube, an electrically conducting liquid partially filling said tubes and adapted to bridge said contacts in opposite ends of the tubes when the tube is tilted alternately into oppositely inclined positions, and means for retarding the progress of the movements of the driver element. 15 20 14. An electric flasher device, comprising a driver element and a driven element pivoted for independent movement in parallel planes and acting upon one another for a snap operation of the driven element in opposite directions when the driver element moves alternately in opposite directions beyond critical intermediate positions, an elongated tube mounted to be tilted into oppositely inclined positions by the driven member during its tilting movements in opposite directions, means for operating said driver element alternately in opposite directions beyond said critical intermediate positions, a plurality of contacts in each end of the tube, means for supplying current to one contact in each end of the tube, an electrically conducting liquid partially filling said tubes and adapted to bridge said contacts in opposite ends of the tubes when the tube is tilted alternately into oppositely inclined positions, and means for retarding the progress of the movements of the driver element in both directions. 25 30 35 40 15. An electric flasher device, comprising a support, a circuit controller mounted on said support for movement therewith into different operative conditions, means for operating said support alternately in opposite directions to cause changes in the circuit controller, a casing in which all of said mechanism is enclosed, means in said casing for controlling the movements of said support and adjustable to vary the intervals between changes in said support, means accessible for operation from the exterior of the casing for varying the effect of the retarding means and thereby varying the intervals between operations of said support, a screw threaded rod mounted for rotation in said casing and extending through a wall thereof, an operating button upon the exteriorly projecting end of said rod, a nut mounted on the threaded part of said rod and held against rotation while being free 45 to move lengthwise of the rod, whereby as the rod is rotated, the nut will be shifted endwise of the rod in one direction or another depending upon the direction of rotation of said button, and means connecting the said nut to said movement controlling means, whereby the intervals between the operations of said circuit controller may be varied without opening said casing. 50 55 60 65 16. An electric flasher device, comprising a driver element and a driven element mounted for independent movement in parallel planes, one of said elements having a pointed end oppositely disposed with inclined surfaces leading to the point thereof, the other of said elements having a longitudinally extending bore opening at one end at a point adjacent the path of the pointed end of the other element, a ball in said bore movable endwise thereof and held against complete projection therefrom at the open end thereof, the projecting portion of the ball being within the path of the pointed end of the other element, a spring in said bore and compressed against said ball to yieldingly hold the ball partially projecting from said bore and within the path of said pointed end, whereby as the said pointed end passes the bore, the ball will move into the bore and ride up an inclined surface leading to the point of the other element and then down the other surface, means for limiting the oscillation of one of the said elements, a circuit controller operated by the said element whose movement is limited, so as to be operated at each change in said element with the limited movement, and means adapted to continuously operate the other of said elements in alternate directions to cause repeated alternate snap movements of the element operating said circuit controller. 70 75 80 85 90 95 100 105 110 115 120 125 130
17. An electric flasher device, comprising a driver element and a driven element mounted for independent movement in parallel planes, one of said elements having a pointed end with oppositely disposed inclined surfaces leading to the point thereof, the other of said elements having a longitudinally extending bore opening at one end at a point adjacent the path of the pointed end of the other element, a ball in said bore movable endwise thereof and restrained against complete projection therefrom at the opening thereof, the projecting portion of the ball being within the path of the pointed end of the other element, a spring in said bore and compressed against said ball to yieldingly hold the ball partially projected from said bore and within the path of said pointed end, whereby as the pointed end passes the bore, the ball will ride up one inclined surface leading to the point of the other element and then down the other surface, means for limiting the oscillation of one of said 135

- elements, a circuit controller operated by the last mentioned element whose movement is limited, so as to be operated at each change in said element with the limited movement, 5 means adapted to continuously operate the other of said elements in alternate directions to cause repeated alternate snap movement of the elements operating said circuit controller, and means for controlling the rate 10 of travel of the last named means, whereby the intervals between operations of the circuit controller may be varied.
18. An electric flasher device, comprising a driver element and a driven element 15 mounted for independent movement in parallel planes, the driver element having oppositely inclined cam surfaces, said driven element having a spring actuated member riding up and down said cam surfaces of 20 the driver element during relative passing movement between said elements, means for limiting the movement of the driven element whereby during oscillations of the driver element in opposite directions beyond 25 critical intermediate positions, the said member of the driven element will be forced to ride up one of said cam surfaces until the critical point is reached and then in riding down the other inclined cam surface will, 30 through the action of its actuating spring, force the driven element to its other limit of movement, a circuit controller operated by said driven element, and means for operating said driver element alternately in opposite directions beyond said critical intermediate positions, said operating means including means for gradually increasing the power available to tension said actuating spring during the movement of said driver 35 element in each direction thereby to compensate for the gradually increasing resistance of said spring.
19. An electric flasher device, comprising a driver element and a driven element 40 mounted for independent movement in parallel planes, the driver element having oppositely inclined cam surfaces, said driven element having a spring actuated member riding up and down said cam surfaces of the driver element during relative movement between said elements, means for limiting the movement of the driven element whereby during oscillations of the driver element in opposite directions beyond critical intermediate positions the contact member of the driven element will be forced to ride up one of said cam surfaces until the critical point is reached, and then in riding down the inclined surfaces will, by the action of its 50 spring, force said driven element to its other limit of movement, a circuit controller operated by said driven element into different operative conditions, means for operating the driver element in one direction, electromagnetic means controlled by said controller for 55 operating said driver element in the opposite direction and storing energy in the prior actuating means, and connections between said driver element and said prior actuating means adapted to gradually increase the effective power of said electromagnetic means in storing energy in said prior actuating means and in concomitantly tensioning said spring, and also adapted to gradually increase the effective power of said prior actuating means in tensioning said spring. 70
20. An electric flasher device, comprising a driver element and a driven element relatively movable and acting upon one another 75 for a snap operation of the driven element in opposite directions when the driver element moves alternately in opposite directions beyond critical intermediate positions, means for effecting the snap operation including a spring arranged to be gradually tensioned during the progress of the movements of the driver element in both directions, means, including a weight, for operating the driver element in one direction, electromagnetic means 80 for operating the driver element in the opposite direction and at the same time elevating said weight for a new operation, a circuit controller carried by said driven element and controlling the activity of said electromagnetic means, so as to cause alternate movements of said driver element, means for retarding the progress of the movements of the driver element in both directions and thereby controlling the intervals of change in the load circuits, and connections between said driver element and said weight adapted to gradually increase the available power of said electromagnetic means and of said weight for tensioning said spring as the tension of the spring increases. 85
21. An electric flasher device, comprising a driver element and a driven element relatively movable and acting upon one another 90 for a snap operation of the driven element in opposite directions when the driver element moves alternately in opposite directions beyond critical intermediate positions, means for effecting the snap operation including a spring arranged to be gradually tensioned during the progress of the movements of the driver element in both directions, means, including a weight, for operating the driver element in one direction, electromagnetic means for operating the driver element in the opposite direction and at the same time elevating said weight for a new operation, a circuit controller carried by said driven element and controlling the activity of said electromagnetic means, so as to cause alternate movements of said driver element, means for retarding the progress of the movements of the driver element in both directions and thereby controlling the intervals of change in the load circuits, and connections between said driver element and said weight adapted to gradually increase the available power of said electromagnetic means and of said weight for tensioning said spring as the tension of the spring increases. 95
22. An electric flasher device, comprising a driver element and a driven element relatively movable and acting upon one another 100 for a snap operation of the driven element in opposite directions when the driver element moves alternately in opposite directions beyond critical intermediate positions, means for effecting the snap operation including a spring arranged to be gradually tensioned during the progress of the movements of the driver element in both directions, means, including a weight, for operating the driver element in one direction, electromagnetic means for operating the driver element in the opposite direction and at the same time elevating said weight for a new operation, a circuit controller carried by said driven element and controlling the activity of said electromagnetic means, so as to cause alternate movements of said driver element, means for retarding the progress of the movements of the driver element in both directions and thereby controlling the intervals of change in the load circuits, and connections between said driver element and said weight adapted to gradually increase the available power of said electromagnetic means and of said weight for tensioning said spring as the tension of the spring increases. 105
23. An electric flasher device, comprising a driver element and a driven element relatively movable and acting upon one another 110 for a snap operation of the driven element in opposite directions when the driver element moves alternately in opposite directions beyond critical intermediate positions, means for effecting the snap operation including a spring arranged to be gradually tensioned during the progress of the movements of the driver element in both directions, means, including a weight, for operating the driver element in one direction, electromagnetic means for operating the driver element in the opposite direction and at the same time elevating said weight for a new operation, a circuit controller carried by said driven element and controlling the activity of said electromagnetic means, so as to cause alternate movements of said driver element, means for retarding the progress of the movements of the driver element in both directions and thereby controlling the intervals of change in the load circuits, and connections between said driver element and said weight adapted to gradually increase the available power of said electromagnetic means and of said weight for tensioning said spring as the tension of the spring increases. 115
24. An electric flasher device, comprising a driver element and a driven element relatively movable and acting upon one another 120 for a snap operation of the driven element in opposite directions when the driver element moves alternately in opposite directions beyond critical intermediate positions, means for effecting the snap operation including a spring arranged to be gradually tensioned during the progress of the movements of the driver element in both directions, means, including a weight, for operating the driver element in one direction, electromagnetic means for operating the driver element in the opposite direction and at the same time elevating said weight for a new operation, a circuit controller carried by said driven element and controlling the activity of said electromagnetic means, so as to cause alternate movements of said driver element, means for retarding the progress of the movements of the driver element in both directions and thereby controlling the intervals of change in the load circuits, and connections between said driver element and said weight adapted to gradually increase the available power of said electromagnetic means and of said weight for tensioning said spring as the tension of the spring increases. 125
25. An electric flasher device, comprising a driver element and a driven element relatively movable and acting upon one another 130 for a snap operation of the driven element in opposite directions when the driver element moves alternately in opposite directions beyond critical intermediate positions, means for effecting the snap operation including a spring arranged to be gradually tensioned during the progress of the movements of the driver element in both directions, means, including a weight, for operating the driver element in one direction, electromagnetic means for operating the driver element in the opposite direction and at the same time elevating said weight for a new operation, a circuit controller carried by said driven element and controlling the activity of said electromagnetic means, so as to cause alternate movements of said driver element, means for retarding the progress of the movements of the driver element in both directions and thereby controlling the intervals of change in the load circuits, and connections between said driver element and said weight adapted to gradually increase the available power of said electromagnetic means and of said weight for tensioning said spring as the tension of the spring increases. 135

cuits, and connections between said driver element and said weight adapted to gradually increase the available power of said electromagnetic means and of said weight for tensioning said spring as the tension of the spring increases, said driver element being pivoted and said connections including

a lever carried thereby, a second lever carrying said weight, and a link pivotally connecting said levers.
